Des. 670

Charles Chinnock, of New York, N.Y.
Letters Patent No. 670, Dated Oct. 17, 1854.

The schedule referred to in these Letters Patent and making part of the same.

To all whom it may concern.

I, Charles Chinnock, of the City, County, and State of New York, have invented a new ornamental design for the front of a clock case, which I term the "Three Bells" pattern, and I do hereby desire that the following is a full, clear and exact description of the same, reference being had to the accompanying drawing, forming part of this specification, in which

Fig. 1. is a front view of a clock case front of my design.

Fig. 2. is a vertical section of the same, through the center.

Fig. 3. is a horizontal section in the line x. y. of fig 1.

Similar letters of reference indicate corresponding parts in the several Figs.

This design is a composition somewhat characteristic of the style of Louis Dauphine, and the Renaissance. It consists of a base A supporting a panel B, which is surrounded with an ornamental frame or border.

The base is paneled, and the stiles are ornamented with rosettes a, a, and with a central flower and leaf ornament b, which unites with the ornamental border of the panel B. It has a moulding c, at the bottom, which unites with or is continued to form feet d, d. The border of the panel B. is composed of scroll and leaf work ornaments e, f, g, h, i, which commence on either side of the ornament b, and extend along the base of the sides and over a crowning piece, j. of leaf work. The opening c, which receives the clock face, is surrounded by a slightly raised ornamental border k, k, terminating in a leaf l, at the bottom.

The design is more particularly intended for casting in iron or other metal and will consist of a single plate made as thin as consistent with a proper degree of strength.

What I claim as my invention and desire to secure by Letters Patent, is
The design and configuration of the clock case front as represented

Dec. 670

in the accompanying drawings and herein described and termed the "Three Bells" pattern.
